UNITED STATES PATENT OFFICE.

KENNETH D. LIGHTHIPE, OF EAST ORANGE, NEW JERSEY, ASSIGNOR TO ELEVATOR SUPPLIES COMPANY, INC., A CORPORATION OF NEW JERSEY.

DESIGN FOR AN ELEVATOR SIGNALING BOX.

Application filed April 29, 1926. Serial No. 17,513. Term of patent 7 years.

To all whom it may concern:

Be it known that I, KENNETH D. LIGHTHIPE, a citizen of the United States, residing at East Orange, in the county of Essex and State of New Jersey, have invented a new, original, and ornamental Design for an Elevator Signaling Box, of which the following is a specification, reference being had to the accompanying drawings, forming part thereof.

Figures 1 and 2 are respectively front and

side elevations of an elevator signaling box, showing my new design. The border which is shown as applied to the top and one side is to be understood to continue in like manner along the other side and the bottom of the box.

I claim:

The ornamental design for an elevator signaling box as shown.

KENNETH D. LIGHTHIPE.
